(57) CLAIM

I claim the ornamental design for a car, toy replica, and/or other replicas, as shown and described.

DESCRIPTION

FIG. 1 is a perspective view of a car, toy replica, and/or other replicas in accordance with the new design.

FIG. 2 is a front view thereof.

FIG. 3 is a rear view thereof.

FIG. 4 is left side view thereof.

FIG. 5 is a right side view thereof.

FIG. 6 is a top view thereof.

FIG. 7 is a bottom view thereof; and,

FIG. 8 is another perspective view thereof.

The broken lines in FIGS. 2-5 and 7 depict portions of the car, toy replica, and/or other replicas that form no part of the claimed design.

1 Claim, 8 Drawing Sheets
